CLAIM

The ornamental design for a spectrophotometer, as shown and described.

DESCRIPTION

FIG. 1 is a front, right perspective view of a spectrophotometer showing our new design.

FIG. 2 is a top plan view thereof.

FIG. 3 is a front elevational view thereof.

FIG. 4 is a left side elevational view thereof.

FIG. 5 is a rear elevational view thereof.

FIG. 6 is a right side elevational view thereof; and,

FIG. 7 is a bottom plan view thereof.

The broken line showing of portions of the spectrophotometer illustrates environmental structure and forms no part of the claimed design.
